UNITED STATES PATENT OFFICE.

RICHARD OTTO MULLER, OF WASHINGTON, DISTRICT OF COLUMBIA.

TURBINE-ROTOR.

1,026,821.

Specification of Letters Patent.

Patented May 21, 1912.

Application filed September 16, 1911. Serial No. 649,755.

To all whom it may concern:

Be it known that I, RICHARD OTTO MULLER, a subject of the German Emperor, residing at Washington, in the District of Columbia, have invented certain new and useful Improvements in Turbine-Rotors, of which the following is a specification.

My invention relates to the class of rotors for radial flow turbines, in which vanes of suitable form project from the side of the rotor body and are consequently subject to severe centrifugal forces tending to produce flexure. In a rotor of this kind, it is necessary to deal successfully with the two destructive agencies of centrifugal force and corrosion, and one object of my invention is to provide a construction in which a material of maximum strength may be used where strength is required, and one of maximum resistance to corrosion, though perhaps of inferior strength, may be used on surfaces subject to objectionable corrosion.

A further object is to provide a construction which can be rapidly assembled from duplicate parts, made in quantities, by inexpensive methods, and kept ready in stock.

A further object is a construction in which the vanes, and the disks or laminations forming the body of the rotor, perform the reciprocal functions of locating and holding each other rigidly together while providing an ample leverage of vane fastening to resist centrifugal action.

These objects are attained in the construction shown in the accompanying drawing in which like symbols are used to designate the same parts throughout, and in which—

Figure 1 is an elevation of the bladed side of the rotor; Fig. 2, a longitudinal section on line A A, Fig. 1; Fig. 3, a similar section showing the internal annular spacing rings omitted from the rotor body; Figs. 4, 5 and 6 show details of the vanes; Fig. 7 is a side elevation of the disk 6 of which the rotor body 7 is principally composed, and Fig. 8 is a side elevation of the annular ring 8, used in the several locations indicated.

Referring to Figs. 4, 5 and 6, 1 is the vane usually made of bronze or other non-corroding material. The longest dimension of its crescent shaped section is located in a radial plane with reference to the rotor body and shaft, and is therefore well adapted to resist centrifugal force. At one end is the

long trunnion 2, adapted to pass through the rotor body and, by the crescent shape which it retains, excepting at the edge where a small portion is cut away to provide a shoulder against which to rivet, is adapted to locate the vane and hold it rigidly in its radial plane. At the other end of the vane is the short trunnion 3 of similar shape, which passes through the shroud ring 4 and is riveted as shown in Fig. 2. The completed vanes may be rapidly cut, each at a single stroke, from a finished rolled bar of crescent shape, by a shear having knives of suitable form.

Fig. 7 shows the rotor disk or lamination 6, of which several are used packed together to constitute the rotor body 7 as shown in Figs. 2 and 3. They are made of sheet metal as thick as can be conveniently punched in duplicate with holes to receive and closely fit the trunnions 2 of the vanes.

Fig. 8 shows the annular ring 8 whose form is like the disk 6 but having more of its center removed. It is also punched from sheet metal and, like the disk, is made of different materials according to the position to be occupied in the rotor. When used in the interior of the rotor body, as for the space rings 9, they are made of steel. When used at the surface, and especially when in contact with rapidly flowing fluid, as at the shrouds 4 and 5, they are made of non-corroding material as brass, bronze or aluminum. When the active part of the vane is of considerable length and consequently needs a correspondingly long trunnion 2 for support, the annular rings are used for spacing between the more active disks 6 located near the surface of the rotor body. Otherwise they are omitted as in Fig. 3. The two outside disks 10 and 11 may also be made of non-corroding material of sufficient strength for self support and then, when all are tightly fastened together, the vane trunnions 2 and 3 serving as rivets as shown in Figs. 2 and 3, the only opportunity for corrosion is at the rotor rim where the edges of the disks are exposed. These edges may now be hammered or burnished down to prevent the entrance of fluid between the laminations and the rotor is practically corrosion proof.

The shroud ring 4 serves to hold the fluid jet against spreading upon its passage

through the vanes. It is composed of the annular rings 8, as in Fig. 8, assembled with the outer trunnions 3 of the several vanes, in the same manner as the rotor body. Here 5 it will be noted that the width of the ring is reduced to an amount only slightly in excess of that of the vanes but with the openings for the trunnions the same as before.

The rotor as above described is mounted 10 upon a suitable hub or center 12, secured to the shaft 13 by any suitable fastening and used in the turbine in the usual manner.

Having thus fully described my invention, what I claim as new and desire to secure by 15 Letters-Patent is:—

1. A radial flow turbine rotor comprising a shaft; a rotor body or wheel mounted thereon, with crescent shaped vanes projecting from the side thereof in a direction 20 parallel with said shaft and having the greatest width of vane lying in a radial plane through said shaft, said rotor body being composed of a set of laminations having duplicate perforations, and so assembled 25 upon a suitable center or hub as to afford a plurality of open passages through the set in a direction parallel with said shaft and adapted to receive and fit the trunnions of said vanes; and said crescent shaped 30 vanes, each having a portion of its edge cut away at one end thus leaving a trunnion of a shape otherwise the same as the body of the vane and adapted to pass through and fit tightly into one of said openings 35 provided therefor in said rotor body, and by riveting, to locate and fasten itself while clamping said laminations tightly together, the whole substantially as and for the purpose set forth.

40 2. A radial flow turbine rotor comprising a shaft; a rotor body or wheel mounted thereon, with crescent shaped vanes projecting from the side thereof in a direction parallel with said shaft and having the greatest width of vane lying in a radial plane through said shaft, said rotor body being composed of a set of laminations having duplicate perforations, and so assembled 45 upon a suitable center or hub as to afford a plurality of open passages through the set in a direction parallel with said shaft and adapted to receive and fit the trunnions of said vanes, part of said laminations, in the interior of said rotor body, being floating annular spacing rings while those near the surface extend inwardly to the hub to which they are firmly secured; and said crescent shaped vanes, each having a portion 50 of its edge cut away at one end thus leaving a trunnion of a shape otherwise the same as the body of the vane and adapted to pass through and fit tightly into one of said openings provided therefor in said rotor body, and by riveting, to locate and fasten itself while clamping said laminations 55

tightly together, the whole substantially as and for the purpose set forth.

3. A radial flow turbine rotor comprising a shaft; a rotor body or wheel mounted thereon, with crescent shaped vanes projecting from the side thereof in a direction parallel with said shaft and having the greatest width of vane lying in a radial plane through said shaft, said rotor body being composed of a set of laminations having 70 duplicate perforations, and so assembled upon a suitable center or hub as to afford a plurality of open passages through the set in a direction parallel with said shaft and adapted to receive and fit the trunnions of said vanes; part of said laminations, at the shoulder of the vane trunnions, being floating annular shroud rings, while others are extended inwardly to the hub to which they are firmly secured; and said crescent 75 shaped vanes, each having a portion of its edge cut away at one end thus leaving a trunnion of a shape otherwise the same as the body of the vane and adapted to pass through and fit tightly into one of said 80 openings provided therefor in said rotor body, and by riveting, to locate and fasten itself while clamping said laminations tightly together, the whole substantially as and for the purpose set forth.

4. A radial flow turbine rotor comprising a shaft; a rotor body or wheel mounted thereon, with crescent shaped vanes projecting from the side thereof in a direction parallel with said shaft and having the greatest width of vane lying in a radial plane through said shaft, said rotor body being composed of a set of laminations having 90 duplicate perforations, and so assembled upon a suitable center or hub as to afford a plurality of open passages through the set in a direction parallel with said shaft and adapted to receive and fit the trunnions of said vanes; a shroud ring composed of annular laminations having duplicate 95 perforations, assembled similarly to said rotor body and adapted to receive and fit other similar trunnions at the outer end of said vanes; and said crescent-shaped vanes, each having a portion of its edge cut away at either end thus leaving a trunnion of a shape otherwise the same as the body of the vane and adapted to pass through, fit tightly and rivet into the openings provided therefor, one end in the said rotor body 100 and the other in said shroud ring, the whole substantially as and for the purpose set forth.

5. A rotor body composed of laminations having duplicate perforations, and so assembled upon a suitable center or hub as to afford a plurality of open passages through the set in a direction parallel with said shaft and adapted to receive, fit and be clamped together by the riveted trun- 105

nions of suitable vanes; said laminations being of a variety of materials, those on the interior being of greater strength and those on the surface of greater resistance to corrosive action, the whole substantially as and for the purpose set forth.

In testimony whereof, I have signed this

specification in the presence of two subscribing witnesses.

RICHARD OTTO MULLER.
